(57) **CLAIM**

The ornamental design for a belt guard, as shown and described.

DESCRIPTION

FIG. 1 is a top, front, right side, open perspective view of a belt guard embodying my design, with the hinge pins removed;

FIG. 2 is a closed right side elevational view thereof with the hinge pins therein;

FIG. 3 is a closed top plan view thereof;

FIG. 4 is a closed rear elevational view thereof along line 4—4 of FIG. 1 with the hinge pins therein;

FIG. 5 is a left side open elevational view thereof; and,

FIG. 6 is a closed bottom plan view thereof.
